MOWING MACHINE HANDLE

Charles W. Butler, Englewood, N. J., assignor to
Toro Manufacturing Corporation of Minnesota,
Minneapolis, Minn., a corporation of Minnesota

Application May 11, 1953, Serial No. 24,954

Term of patent 14 years

(Cl. D40—1)

To all whom it may concern:

Be it known that I, Charles W. Butler, a citizen of the United States of America, residing at Englewood, county of Bergen, State of New Jersey, have invented a new, original, and ornamental Design for a Mowing Machine Handle, of which the following is a specification, reference being made to the accompanying drawings forming a part thereof, and in which:

Fig. 1 is a plan view of a mowing machine handle, embodying my new design; and

Fig. 2 is a side elevational view of the same.

I claim:

The ornamental design for a mowing machine handle, substantially as shown.

CHARLES W. BUTLER.
